INVENTOR

James T. Swain

UNITED STATES PATENT OFFICE.

JAMES T. SWAIN, OF PITTSBURG, PENNSYLVANIA.

BOLTING OR CLAMPING DEVICE.

SPECIFICATION forming part of Letters Patent No. 559,506, dated May 5, 1896.

Application filed January 22, 1896. Serial No. 576,423. (No model.)

To all whom it may concern:

Be it known that I, JAMES T. SWAIN, a citizen of the United States, residing at Pittsburgh, in the county of Allegheny and State of Pennsylvania, have invented an Improvement in a Bolting or Clamping Device; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to an improvement in a bolting or clamping device to be used on a face-plate or platen, as shown in the accompanying drawings, in which—

Figure 1 is an end view of the device; Fig. 20 2 a side view, and Fig. 3 a perspective view, of a section of a table, in which the device is shown in position ready for use.

Similar letters refer to similar parts throughout the several views.

25 The pieces A and B constitute the device. The bolt C shows a bolt in position ready for use. The device is put in position by dropping one part, either A or B, in the slot, and then dropping the other part in at the end of 30 the first one and sliding it beside the other, as shown in cuts. The two pieces A and B are in every way alike, and are interchangeable. In my device I claim a great improvement over all other ways of bolting or clamping.

35 The following are a few of the advantages of my invention. When used on a planer, the slots in the table do not have to be cleaned out, except the lengths of the pieces, and 40 even that can almost be done with them. If a bolt breaks, another can easily be put in instead. The work can be laid on the table before the bolts are set, thereby saving time in measuring bolts. In case, after the work is 45 set on the table, it is found that the bolts are

in the wrong place, or that they are either too long or too short, or that it would be better to clamp on some other part of the work, or that the bolts do not hold sufficiently, they can be changed or the numbers increased without trouble.

The slots used for bolting purposes are not spoiled, as they are by the use of T-head bolts, as they take a good grip in the slot. Bolts with common heads can be used instead of special bolts made to fit the slots. Bolts with much heavier heads can be used than those made to fit the slot in the machine.

The device is very useful on boring and turning mills. In turning off the outside of 60 wheels and the like bolts can be put inside and changed to the outside when finishing the inside. In putting on or taking the work off the table can be clear. The cross-head does not have to be raised to get the work over 65 bolts.

I am aware that by the use of T-head bolts some of these difficulties are overcome; but as I have before stated they break the corners off the inside of the slots and in time 70 spoil the table, and also the bolt-heads have to be thin and narrow, and the bolts sometimes turn while being loosened and the work when overhanging the table is liable to fall off.

Having fully described my invention, what 75 I claim, and desire to secure by Letters Patent, is—

An improvement in a bolting or clamping device, consisting of two symmetrical parts A and B, each being provided with a half-T-slot 80 for receiving the head of a bolt and a half-T-shank, adapted to slide in the T-slot of a face-plate or platen, substantially as described.

In testimony whereof I affix my signature in presence of two witnesses.

JAMES T. SWAIN.
